UNITED STATES PATENT OFFICE.

HARRY A. STEERE, OF SAN FRANCISCO, CALIFORNIA.

DESIGN FOR AN ELECTRIC POPCORN POPPER.

Application filed April 25, 1928. Serial No 26,458. Term of patent 14 years.

To all whom it may concern:

Be it known that I, HARRY A. STEERE, a citizen of the United States, residing at the city and county of San Francisco, State of California, have invented a new, original, and ornamental Design for Electric Popcorn Popper, of which the following is a specification, reference being had to the accompanying drawing, forming part thereof.

The drawing is a perspective view of the electric popcorn popper showing my new design.

I claim:

The ornamental design for an electric popcorn popper, substantially as shown.

HARRY A. STEERE.
